UNITED STATES PATENT OFFICE.

RICHARD HOWARD SNAPE, OF BRIDGETOWN, NOVA SCOTIA, CANADA, ASSIGNOR OF THIRTY ONE-HUNDREDTHS TO FREDERICK L. DAVIDSON, OF HALIFAX, NOVA SCOTIA, CANADA.

WASHING AND DRYING MACHINE.

1,293,962.

Specification of Letters Patent. Patented Feb. 11, 1919.

Application filed March 18, 1918. Serial No. 223,194.

To all whom it may concern:

Be it known that I, RICHARD HOWARD SNAPE, a subject of the King of Great Britain, and resident of Bridgetown, in the 5 county of Annapolis, in the Province of Nova Scotia, Dominion of Canada, have invented certain new and useful Improvements in Washing and Drying Machines, of which the following is a specification.

- 10 This invention relates to washing and drying machines for dishes and other articles, and the objects of the invention are to facilitate washing and drying the articles by primarily splashing them with a liquid and 15 subsequently drying them by creating and passing a current of drying fluid around and between them to permit of the magnitude of the splashing or force of the drying current or fluid being controlled and altered to suit 20 the requirements of the machine, to adapt the machine for household, hotel, or other purposes, and generally to adapt the several parts to better perform the functions required of them.
- 25 With the above and other objects in view, the invention consists essentially of the improved construction, particularly described and set forth in the following specification and accompanying drawings forming part 30 of the same.

In the drawings;

Figure 1 is a front elevation of the improved machine.

Fig. 2 is an end elevation of the machine, 35 part being broken away to show the operating mechanism.

Fig. 3 is a transverse sectional elevation on the line A—A of Fig. 1.

Fig. 4 is an enlarged fragmentary longitudinal sectional view of one end of the machine showing the splashing element and means for operating the same.

Fig. 5 is an enlarged fragmentary longitudinal view of the other end of the machine 45 showing the boiler.

Fig. 6 is an enlarged detailed view showing the means, whereby the splashing element may be disengaged and withdrawn from the casing.

50 Fig. 7 is a perspective view of one of the removable trays used with the machine.

Like characters of reference refer to like parts in the several figures.

Referring to the drawings, the improved machine consists of a casing 8 constructed of 55 any suitable material, and provided with a cover 9 attached to the top by hinges 10 or the like, the cover being formed with a handle 11 whereby the said cover may be opened to permit of the articles to be washed being 60 placed within the casing.

The casing 8 is mounted on suitable legs 12 connected by rods 14 which brace the legs and give to the supporting frame so formed, considerable strength, besides permitting of 65 light material being used in the construction.

On the lower end of the casing, a longitudinally extending trough 15 is provided to permit of the dirty washing liquid being 70 drawn or drained off through the outlet 16.

It is also desirable that the washing liquid should be heated, and to this end I provide a heating device, which, in the embodiment illustrated, is in the form of an oil stove 18, 75 to which fuel is supplied through a pipe connected to the oil reservoir 19. Other heating devices, such as a gas ring or electrical means can also be used with equal success.

The boiler 17 is formed on the upper end 80 with an opening 19' through which water is poured into the boiler, and this opening may be normally closed by a cover.

The boiler is connected to the casing 8 through a valve 20 located near the bottom 85 of the boiler, and this valve is operated by a rod 21 which extends through the upper wall of the boiler, where it is provided with a suitable handle 22, so that the operator may open the valve and so permit of the 90 heated water passing into the casing.

The means which I employ to agitate or splash the water in the casing 8 on the articles being washed consists of a removable paddle wheel or propeller 23 formed of suitable material and provided with peripheral vanes 33, one face of each of which vanes is substantially flat, while the other face is flattened for only a part of its height, and then extends angularly backwardly to the 100 adjacent vane.

The area of the larger flattened face is al-

most twice the area of the opposite flattened face of the vane.

The wheel or propeller 23 is carried by an axle formed in two portions 24 and 28 5 operatively secured together, the first portion having one end journaled in the bearing 25 mounted on the end wall of the casing adjacent to the boiler, while the other end is reduced to form a tongue 26 designed to engage 10 with a recess 27 formed in the inner end of the axle 28.

The axle 28 is journaled in the bearing 38, mounted on the end of the casing 8 and also in the bearing 35 mounted on the 15 guard 34.

When the axles 24 and 28 are abutted with the tongue 26 engaging with the recess 27, a collar 29 slidably mounted on the axle 28 is forced over the abutting ends of the said 20 axles by a compression spring 30 which encircles the axle 28. When the collar is withdrawn from this position it may be held in retracted position by a pin 32 on the axle 28, which pin engages with an angle slot 25 31 in the collar.

The axle 28 is designed to rotate the splashing paddle or propeller 23 and carries a gear 40 which meshes with a gear 41 carried by an intermediate axle 37 journaled 30 in the bearings 39 and 36 mounted on the casing 8 and guard 34 respectively.

The gear 41 may be formed integral with a grooved or like pulley 42 designed to be driven from an electric motor or other prime 35 mover when the splasher is to be operated by power.

If the machine is of small capacity it will preferably be driven by hand and a grooved pulley 44 is provided on the intermediate 40 axle 37 and connected by a flexible member 45 to a grooved pulley 46 mounted on the axle 47 journaled in the bearings 48 and 49 which are carried by the casing 8 and bracket 50 respectively.

45 The axle 47 is adapted to be manually rotated by a crank handle 51 secured to the outer end thereof by a set screw 52 or other like means.

In the casing 8, a flange 54 or like supporting member is secured to the walls intermediate of the height thereof, and on this flange the removable tray 53 rests.

This tray is preferably formed of wire 56 so that it will not interfere with the action 55 of the water, and a plurality of plate supporting members 55 of inverted U-shape and also formed of wire are provided so that when plates are being washed they will be held vertical, and thus the washing water 60 or liquid will be splashed on both sides thereof to effectively clean the same.

The operation of the several parts will be readily understood from the foregoing description.

65 When the machine is in operation, the lid

9 is opened and a tray 53 of articles to be washed is placed within the casing, the said tray resting on the flange 54. Water is now poured into the boiler 17 through the opening 19 and the heater 18 is lighted to bring 70 the water in the said boiler to the desired temperature.

When the water has been heated to a sufficient degree, the operator actuates the rod 21 by means of the handle 22 and so opens 75 the valve 20 and permits of the heated water passing from the boiler 17 into the casing 8.

It will be understood that the discharge or outlet 16 will be normally closed, so that 80 the water delivered to the casing 8 will lie in the trough 15. The lid 9 of the casing 8 is now closed and rotary motion is manually transmitted to the axle 47 through the crank handle 51. The pulley 46 through the flexible member 45 transmits rotary motion to the pulley 44 and axle 37 which through the intermeshing gears 41 and 42 rotates the axle 28 and 24 so rotating the paddle wheel or propeller 23 and splashing 90 the water in the trough 15 upwardly around and between the dishes or articles placed on the tray 53.

It will be understood that the ratio of the gears 40 and 41 and the pulleys 44 and 46 95 will be such that while an easy and even motion is given to the crank handle 51, the desired speed of rotation will be transmitted to the splashing paddle or propeller.

It may be found advisable in some circumstances to remove the splashing paddle or propeller 23 and this is readily accomplished by drawing back the collar on the shaft 28 and engaging the slot 31 with the pin 32 so holding the collar in retracted position and permitting of the tongue 26 to become disengaged from the recess 27 in the axle 28 and so allowing the splashing paddle or propeller 23 being disengaged and lifted out of the casing 8. The removal of 100 the paddle or propeller may be for inspection or other means.

When the articles on the tray 53 have been splashed for about a minute or so, they will be cleaned and the water can now be 115 drained out of the casing 8 through the outlet 16 which will now be left open. After the water is drained from the casing, the crank handle 51 is again rotated and the splashing paddle or propeller 23 will now 120 act as a fan and create a current of air which will be forced upwardly between and around the articles on the tray 53 so effectively drying the same.

Under normal washing circumstances the 125 propeller or splashing paddle 23 will be rotated in a counterclockwise direction so that the broad face of the peripheral vanes 33 will create a maximum splashing effect but if it is found advisable to reduce this 130

splashing effect the propeller 23 is rotated in a clockwise direction, so that the smaller flattened face of the vanes 23 will now engage with the washing liquid and the 5 splashing will consequently be reduced.

This same movement applied also to the creating of a drying current of air as by rotating the propeller 23 in an anti-clockwise direction, a maximum current of air 10 will be rotated, whereas by rotating the said propeller in a clockwise direction a minimum current of air may be created.

From this description it will be seen that I have invented a washing and drying machine which can be advantageously utilized in households or in public places, such as 15 hotels and restaurants, so that an effective washing and drying of dishes and like articles can be readily effected without any un- 20 sanitary washing cloths or towels coming in contact with the said articles, the said machine being of a compact construction with the several working parts readily accessible for inspection, and not liable to go out of 25 repair.

As many changes could be made in the above construction and many apparently widely different embodiments of my invention within the scope of the claims, constructed without departing from the spirit 30 or scope thereof, it is intended that all mat-

ter contained in the accompanying specification and drawings shall be interpreted as illustrative and not in a limiting sense.

What I claim as my invention is:

35

1. A washing and drying machine of the class described, comprising a casing, means in the casing for holding the articles to be washed, and a splashing device, comprising a paddle wheel having peripheral vanes 40 formed with one face flat, and the opposite face flat for only part of the height thereof, and then sloping back toward the adjacent vane.

2. A washing and drying machine of the 45 class described, comprising a casing, means in the casing for holding the articles to be washed, and a splashing device comprising a paddle wheel, a pair of abutting axles supporting the paddle wheel, a collar having an 50 edge bayonet slot slidably mounted on one of the axles, a pin on the axles, supporting the collar, and adapted to engage with the said slot when the collar is in retracted position, and a spring designed to hold the collar in normal position.

In witness whereof I have hereunto set my hand in the presence of two witnesses.

RICHARD HOWARD SNAPE.
